UNITED STATES PATENT OFFICE

KENNETH E. BEMIS, OF GLENDALE, CALIFORNIA

DESIGN FOR A BUILDING STRUCTURE

Application filed June 20, 1932. Serial No. 44,146. Term of patent 14 years.

To all whom it may concern:

Be it known that I, KENNETH E. BEMIS, a citizen of the United States, residing at Glendale, in the county of Los Angeles and State of California, have invented a new, original, and ornamental Design for Building Structure, of which the following is a specification, reference being had to the accompanying drawing, forming part thereof.

Fig. 1 is a disclosure of the interior of the

building shown in Fig. 2, and embodies the novel features of the design. Fig. 2 is a perspective view of the exterior of a building of the type embodying the present design, and disclosed in my Design Patent #85,317.

I claim:

The ornamental design for a building structure as shown and described.

KENNETH E. BEMIS.
